CLAIM

The ornamental design for a knife blade sharpener or the like, substantially as shown and described.

DESCRIPTION

FIG. 1 is a perspective view of an apparatus for sharpening a knife blade or the like showing my new design;

FIG. 2 is a top view thereof;

FIG. 3 is a first end view thereof;

FIG. 4 is a first side elevation view thereof;

FIG. 5 is an opposite end view from that of FIG. 3;

FIG. 6 is an opposite side elevation view from that of FIG. 4; and

FIG. 7 is a bottom view thereof.
